GARMENT POCKET

Anna Peters, San Antonio, Tex.

Application January 6, 1934, Serial No. 705,480

2 Claims. (Cl. 2—254)

My invention relates to improvements in garment pockets and the main object is to provide a pocket particularly suitable for carrying a watch or other small valuable article and so arranged 5 and provided that the watch can not accidentally fall from the pocket when the wearer stoops or bends over, the pocket being thus of great utility for the shirts, overalls or like garments for railroad and other workers.

10 Another object is to provide a pocket of this kind of simple, practical and neat form and having the general exterior appearance of the usual patch pocket.

A further object is to provide a pocket including 15 an outer patch portion attached along vertical lines to the garment for a short distance downward from the top on one side and for a considerably longer distance downward on the other side, and a pouch portion folded upward and inward and attached to the free side and bottom margins of the patch portion and at its upper edge along a diagonal line to the garment.

With these and other objects in view the invention resides in the novel construction and arrangement of parts as hereinafter fully set forth and claimed, reference being had to the accompanying drawing, wherein:

Figure 1 is an elevation of my improved pocket as attached to a garment, only a fragment of the latter being shown.

Figure 2 is a view similar to Figure 1 but showing a part of the patch portion of the pocket as broken away to disclose the diagonal attaching line at the top of the pouch portion.

Figure 3 is an edge view of the pocket.

Figure 4 is a vertical section showing the position assumed by the pocket when the wearer stoops or bends over and showing a watch in dotted lines in the pocket.

Figure 5 is a plan view on a reduced scale of the blank from which the pocket is formed.

In carrying out my invention I provide a blank 45 6 of suitable fabric so shaped and cut as to form a substantially rectangular patch portion 7 and attached pouch portion 8, the free and intended top edge of the patch portion and the lower corners 10 of both the patch and pouch portions being suitably rounded and shaped as desired to form a pocket of neat appearance. The free and

50 intended upper end or edge 11 of the pouch portion 8 is cut off angularly or diagonally relative to the sides as clearly shown in Figure 5. The pouch portion 8 is then folded up inwardly along the line 12 alongside the patch portion 7 and the lateral margins are turned inward and sewed

5 together as at 13 so that a pouch designated generally at 14 is provided. The exposed free lateral margins of the patch portion 7 are next sewed to the garment A as at 15 from the top 9 down to the upper diagonal pouch edge 11 and this edge is 10 then sewed to the garment as designated at 16. The resulting formation or arrangement is such that the lower pouch portion of the pocket may swing free of the garment from the points B and C, the upper margin or end of this free swinging portion being defined and falling along the diagonal sewed or fastened margin 11. Then with 15 a watch D or other similar object placed in the pouch 14, this pouch will swing outward at its lower end from the garment A as the wearer bends 20 forward (Figure 4) and will at all times hang in a vertical plane so that the watch cannot fall or slide out of the pocket as will be readily understood. To further aid in this holding the watch in place the tendency is for the patch portion 7 25 of the pocket to crimp or pinch in along the diagonal line B to C when the pouch swings outward as designated at 17 in Figure 4. The pocket swinging or folding on a diagonal line also causes the watch to normally move over into and rest 30 in the deeper side of the pouch and pocket. This constitutes an important feature of the invention resulting directly from the angularity of the line B to C and edge 11 and keeps the watch from sliding from side to side with consequent wear and 35 shock to the case and mechanism. One vertical side margin of the pocket may be arranged as a receptacle for a pencil E by sewing the patch portion 7 down to the garment above the upper edge 11 of the pouch portion as shown at 18. This pencil receptacle also serves to restrict the opening leading into the watch pouch, thereby further lessening the danger of loss of the watch or the like placed within the pouch.

It will be apparent that a pocket formed and 40 fastened to the garment as set forth will present a neat appearance, will be as simple and inexpensive as the usual pocket and will positively hold and secure a valuable watch or other article against falling while the wearer stoops or bends 45 at his work. The pocket is thus especially suited for work shirts, overalls and other work garments but may, of course, be used on any other desired and suitable garment.

While I have herein set forth a certain preferred embodiment of my invention it is understood that I may vary from the same in minor details so as best to provide a practical arrangement for the purposes in view, not departing from 50

the spirit of the invention and within the scope of the appended claims.

I claim:

1. The combination with a garment which would normally be inclined forwardly as the wearer bends forwardly, of a pocket secured to the outer side of the garment, the same comprising an outer and substantially rectangular patch portion and a shorter, inwardly and upwardly turned pouch portion, the latter being cut off diagonally at its up-turned margin and thereby attached to the garment, the sides of the patch portion above the diagonal margin of the pouch portion being also attached to the garment, thereby forming a pouch, which under the weight of a watch or the like placed therein, will, as the garment is inclined forwardly, swing outwardly from the garment at its lower end and hang in a vertical plane from its diagonal line of connection to the garment, with the watch in the deeper corner of the pouch.
2. In combination with a portion of a garment normally inclinable forwardly with the wearer thereof, a pocket attached to the outer side there-

of, the same comprising an outer patch portion and a shorter, inwardly and upwardly turned pouch portion, the latter being extended diagonally at its upper margin relative to the lateral margins of the patch portion and being thereby attached to the garment, the sides of the patch portion above this diagonal upper margin of the pouch portion being also attached to the garment by seams adapted to stand vertically with the wearer of the garment, the longer side margin of the patch portion being also attached to the garment on a line spaced inwardly from and extended parallel to the outer and longer marginal line of attachment of the patch portion, thereby providing both a pouch having an upwardly disposed opening and a separate pencil receptacle restrictive of the pouch opening, whereby with an object within the pouch and the garment inclined forwardly, the pouch will swing outward from its diagonal line of connection to the garment, thereby safeguarding the said object against falling out of the pouch.

ANNA PETERS.
